PRESSURE-RESPONSIVE SWITCH

Edwin W. F. Hanke, Whitefish Bay, Wis., assignor
to Allen-Bradley Company, Milwaukee, Wis., a
corporation of Wisconsin

Application July 30, 1941, Serial No. 404,629

5 Claims. (Cl. 200—83)

This invention relates to electrical switches of the type which respond to alter an electrical circuit when forces of predetermined intensity are caused to act thereon through a fluid-pressure device or other effective instrumentality. The invention more specifically resides in a novel arrangement and formation of parts in such a switch, which arrangement employs as the calibrated counterloading element a leaf spring, the ends of which are restrained. In this apparatus the actuating force is applied between the ends of the calibrated spring to cause the central portion thereof to be deflected and such deflection is communicated to an over-center snap action device for controlling electrical circuit elements.

Among the advantages of the above novel arrangement are the ease with which a strip or leaf spring having a definite calibration can be formed and the ease with which the ends of such a spring can be adjustably mounted for variation of the response of the switch. Another advantage is the very flat, compact space occupied by the calibrated counterloading elements of the apparatus.

Another advantage is the simplicity of the construction and the small number of parts required. All of these advantages contribute toward the accomplishment of a major object of this invention which is to provide a reliable and accurate switch at a substantial saving in cost as compared with pressure switches heretofore known and used.

The apparatus of this invention is hereinafter more particularly described by reference to the accompanying drawings forming a part hereof. In the drawings there is set forth by way of illustration and not of limitation one particular form of the apparatus of this invention. The several figures of the drawings are briefly described as follows:

Fig. 1 is a side elevation, in section, of a pressure switch constructed in accordance with this invention;

Fig. 2 is a fragmentary plan view, in section, viewed through the plane indicated in Fig. 1 by the line 2—2, showing in greater detail the counterloading spring and its mounting;

Fig. 3 is a detail view, in perspective, of the horizontally adjustable stop;

Fig. 4 is a plan view of the pressure switch shown in Fig. 1, a portion of the base being shown broken away;

Fig. 5 is a detail sectional elevation of the over-

center switch parts in position opposite to that shown for the same parts in Fig. 1; and

Fig. 6 is a detail view, in perspective, of the lower side of the counterloading spring and its mounting.

More particularly described, the apparatus of this invention, as depicted in the drawings, is mounted upon and partially housed by a frame 1. The frame 1 is formed from heavy sheet metal by bending upwardly from the horizontal base portion 2 thereof two similar vertically-standing side walls 3, only one of which appears in the drawings. A circular indentation 4 formed in the material of the base is positioned as shown in Fig. 1 to accommodate a pressure-foot 5. Secured to and projecting upwardly from the foot 5 is an actuator 6, which passes through an aperture in the indentation 4, as shown.

Against the lower exterior face of the base 2, a flexible rubber diaphragm 7 is securely clamped in place in position to cooperate with the pressure-foot 5. Clamping is accomplished by means of pressure-chamber 8 and screws 9 which engage tapped openings in the base 2. Integrally formed with the pressure chamber 8 is a tapped boss 10 for attachment to the fluid-pressure system to which the switch is intended to respond.

As a counterloading means for balancing the pressure in chamber 8, a resilient strip or leaf-spring 11 is provided. Spring 11 is composed of thin resilient stock, such as clock-spring steel or the like, and is of nearly rectangular shape except for a pair of ears 12 which project from one end. The spring 11 is restrained against endwise and sidewise displacement by a bracket 13, which is secured by the rivet lugs 15 to the base 2 as shown in Fig. 1. As appears more clearly in Fig. 6, endwise displacement is restricted by reason of the fact that spring 11 has an effective length close to, but slightly less than, the distance between the downwardly extending portions of the bracket 13. Sidewise displacement, on the other hand, is restricted by engagement of the ears 12 with sockets or openings in the right-hand vertical portion of bracket 13 and by the rectangular configuration of the spring 11. The spring 11 is further held against lateral displacement by the nose 16 on the upper end of the actuator 6, said nose passing through a perforation in the spring 11 provided for that purpose.

In order to restrain the spring 11 against transverse movement on opposite sides of the point of engagement of the actuator 6 therewith,

there is provided a vertical adjusting screw 17 and a horizontally adjustable stop 18. The vertical adjusting screw passes through a tapped opening in the top of the bracket 13 and is positioned so that its lower end engages the left-hand end of spring 11 in order that the transverse position at which the spring 11 is held may be regulated as desired. The stop 18, on the other hand, is of the form shown clearly in Fig. 3, where it appears that it is provided with a tapped opening 20 and a small vertical projection 19 above the tapped opening.

The top of bracket 13, near the right-hand end, is provided with a slot 21 so dimensioned as to receive the projection 19 of the stop 18. In addition, the vertical portion of the bracket 13, at the right-hand end, is notched to receive the head of a horizontal captive screw 22, the threaded portion of which is in engagement with the tapped opening 20 of the stop 18. By reason of this construction, regulation of screw 22 permits the positioning of the horizontally adjustable stop 18 at any horizontal position within its range of movement.

The vertical adjusting screw 17 and the horizontal stop 18 cooperate to resist the transverse thrust which the actuator switch applies to the spring 11 when fluid-pressure acts upon the diaphragm 7.

By reason of the lateral clearance between the spring 11 and the bracket 13, no appreciable friction is involved in transverse displacement of the spring 11 by the actuator 6. There is thus obtained reliable and consistent counterloading by means of the spring 11, because the elastic properties of the spring 11 are the primary factor in determining the strength of the counterloading. Because of the extreme simplicity of the shape of the spring 11 and because of the ready availability of material of good quality from which the spring is made, such a spring having the desired initial calibration can be very economically formed. While it is preferable to employ a spring which is flat in its unstressed state, since such a spring is more easily constructed, a slight bowing of the spring in unstressed condition is not objectionable.

Mounted upon the bracket 13 by means of mounting screws 23, 23 is an insulating support 24 to which the over-center switch parts are secured. These parts comprise a thin resilient metallic strip 25 of somewhat elongated shape, within which there is lengthwise disposed an elongated U-shaped aperture 26 which serves to form the tongue 27. Between the pointed end of the tongue 27 and a pointed projection 28 formed at the base of the U-shaped aperture 26 a small compression spring 29 is interposed. The ends of the spring 29 are provided with indented cups, as shown, to facilitate engagement with the projection of tongue 27 and with the projection 28.

By reason of the cooperation between spring 29 and member 25, spaced forward and return over-center positions are exhibited by these parts. The member 25 is securely anchored at its left-hand end by means of rivets 30, 30 and the motion-limiting stop 31. The stop 31 also serves as a mounting for electric terminal screw 32. Upon the right-hand end of member 25 there is carried a pair of electrical contact buttons 33 which are arranged to act between stationary contacts 34 and 35. As shown in Fig. 1, the movable contact buttons 33 are in electrical engagement with stationary contact 34. In this posi-

tion the diaphragm 7 is relaxed and the transverse displacement of spring 11 is at a minimum. In this position the thruster 36 bears with little or no pressure against the tongue 27 of the over-center switch.

In Fig. 5 the over-center switch parts are shown in the position assumed when sufficient pressure is applied in chamber 8 to displace the diaphragm 7 and to transversely deflect the central portions of the spring 11. When this occurs the thruster 36 is caused to act upon the tongue 27, moving the same until the over-center parts snap to the position shown in Fig. 5.

Because of the spacing of the over-center positions of the switch parts 25 and 29, the pressure switch above described is of the differential type, that is to say, the pressure at which the switch responds while pressure is increasing differs from the pressure at which the switch responds when pressure is decreasing. Therefore, by adjustment of the vertical adjusting screw 17 the level at which the differential occurs may be regulated within limits as desired without substantial alteration of the amount of the differential. However, if it is desired to alter the magnitude of the differential, this may be accomplished by adjustment of the horizontally adjustable stop 18. In general, the closer the horizontal stop 18 to the actuator 6 the greater will be the amount of the differential for any given setting of the vertical adjusting screw 17. Of course the level at which the differential occurs is also altered to some extent by adjustment of the horizontal stop 18. However, by selecting the proper position of adjustment for the vertical adjusting screw 17 and the horizontal stop 18, both the level and the amount of the differential may be adjusted as desired, within limits. Of course, if regulation of the amount of the differential is not desired, the horizontal stop 18 need not be moved, or may be omitted, or formed as a non-adjustable part of the apparatus. It is also apparent that the spring 11 may be formed of a single leaf, as shown, or may be of laminated construction, employing several superimposed leaves, if a more intense counterloading action is desired.

It will be apparent from the above description that the apparatus of this invention provides a very simple and economically constructed counterloading means and one which occupies a relatively small vertical height, thus facilitating a very compact structure for a switch of this character. This permits the use of contacts of adequate size and the provision of ample wiring space within a housing of moderate size. These advantages are obtained in spite of the saving in cost and the simplification of the counter-loading means, all without sacrifice of complete adjustability and reliable and consistent response.

That which I claim as my invention is:

1. In a pressure-responsive electrical switch, the combination comprising a calibrated counterloading means in the form of a leaf spring, a base, mounting means associated with said base for preventing endwise and sidewise displacement of said spring and for retaining spaced portions of said spring against transverse movement, a pressure-responsive actuator mounted on said base and positioned to act transversely upon said spring between said transverse retaining means to deflect said spring transversely therebetween, and an over-center switch in cooperative engagement with the transversely deflectable portion of

said spring adapted to be actuated by transverse deflection thereof.

2. In a pressure-responsive electrical switch, the combination comprising a calibrated counterloading means in the form of a leaf spring, a base, mounting means associated with said base for preventing endwise and sidewise displacement of said spring and for retaining spaced portions of said spring against transverse movement, said mounting means including adjustable means for adjusting the transverse position at which one portion of said spring is retained, a pressure-responsive actuator mounted on said base and positioned to act transversely upon said spring between said transverse retaining means to deflect said spring transversely therebetween, and an over-center switch in cooperative engagement with the transversely deflectable portion of said spring adapted to be actuated by transverse deflection thereof.

3. In a pressure-responsive electrical switch, the combination comprising a calibrated counterloading means in the form of a leaf spring, a base, mounting means associated with said base for preventing endwise and sidewise displacement of said spring and for retaining spaced portions of said spring against transverse movement, said mounting means including adjustable means for adjusting the transverse position at which one of said spaced portions of said spring is transversely retained, additional adjustable means for adjusting the endwise position at which the other of said spaced portions is transversely retained, a pressure-responsive actuator mounted on said base and positioned to act transversely upon said spring between said transverse retaining means to deflect said spring transversely therebetween, and an over-center switch in cooperative engagement with the transversely deflectable portion of said spring adapted to be actuated by transverse deflection thereof.

4. In a pressure-responsive electrical switch,

the combination comprising a calibrated counterloading means in the form of a thin strip of resilient material, a base, mounting means associated with said base comprising loose socket means for engagement with one end of said strip and retaining means for preventing removal of said end from said socket, a pair of stops engaging spaced portions of the upper surface of said strip for preventing transverse movement of said portions, a pressure-responsive actuator mounted on said base and positioned to act transversely upon said spring between said stops to deflect said spring transversely therebetween, and an over-center switch in cooperative engagement with the transversely deflectable portion of said spring adapted to be actuated by transverse deflection thereof.

5. In a pressure-responsive electrical switch, the combination comprising a calibrated counterloading means in the form of a thin strip of resilient material, a base, mounting means associated with said base comprising a vertically projecting loose socket means for engagement with one end of said resilient strip and a vertically projecting retainer adjacent the other end of said strip for preventing endwise and sidewise displacement of said strip, a vertical adjusting screw in adjustable engagement with the top of one end of said strip, a horizontally adjustable stop in engagement with the upper surface of the portion of said strip opposite the end thereof engaged by said vertical adjusting screw, a pressure-responsive actuator mounted on said base and positioned to act transversely upon said strip to transversely deflect the same between said vertical adjusting screw and the zone of adjustment of said horizontally adjustable stop, and an over-center switch in cooperative engagement with the transversely deflectable portion of said strip adapted to be actuated by transverse deflection thereof.
